STRAIGHT HANDLED VIBRATORY RAZOR

Filed Nov. 21, 1924

UNITED STATES PATENT OFFICE.

SAUL SHALER, OF NEW YORK, N. Y., ASSIGNOR TO HENRY B. COHEN, OF NEW YORK, N. Y.

STRAIGHT-HANDED VIBRATORY RAZOR.

Application filed November 21, 1924. Serial No. 751,225.

This invention relates to safety razors of the class in which a relatively thin blade is confined upon a base constructed with guard fingers, and usually referred to as the comb, 5 by means of a removable cap; the blade being held against displacement in the plane of the razor by means of pins fixed upon one of the confining members and passing through openings in the blade.

- 10 In my application, Ser. No. 678,136, filed December 3, 1923, I have disclosed a razor with a blade and mounting arranged in this manner, but in which the handle extends from the mounting in a direction substantially perpendicular to the plane of the blade, the blade being arranged to vibrate upon the mounting by having the openings which receive the fixed pins elongated in the direction of vibration, and the handle being equipped with electrically energized vibratory mechanism, one element of which extends from the handle in a position to impart vibration to the blade.

The primary object of the present invention is to adapt a suitable vibratory mechanism, for instance, that described in my application above identified, to a razor having its blade mounted in substantially the manner aforesaid, but in which the handle is in the nature of a shank or shaft extending in a direction substantially parallel to the plane of the blade after the manner of a so-called straight razor; and accordingly one feature of the present invention consists in mounting a vibrator at or near one end of a laterally offset shank or handle and the vibratory razor blade at the other end thereof, while the intermediate portion of the shank serves for prehension in the manipulation of the razor; and connecting the transmitting member of the vibrator with the blade through means of a longitudinally reciprocating thrust member mounted in the handle or shank and provided at its respective ends with means for establishing driving connection with the blade and the transmitting member.

A further object is to provide a design of connecting rod which will be very cheap to produce in accurate form, very light in structure, readily responsive to vibratory force and very conveniently assembled and disassembled with the shank or handle and with the elements with which it cooperates at its respective ends. Accordingly another feature of the invention consists in constructing

the shank or handle in tubular form, preferably of two members united through longitudinal tongue and groove joints so that one slides into position upon the other, and confining the connecting rod in the housing thus provided and between the said members thereof in a manner to guide it in its right-line movement without imposing undue frictional or other resistance to its action; the end of the connecting rod which receives the vibrating element being fashioned in the form of a yoke which embraces said element when the vibratory mechanism is placed in position upon the handle, and the end of the connecting rod which drives the blade being in the form of a slide fitted in a bed formed in the guard and carrying a stud which projects through a central opening in the blade.

A still further object is to coordinate the vibrator and the shank of a vibratory razor, such as above referred to, in a manner to admit of convenient rotation of the head of the razor and its shank about their longitudinal axis relatively to the vibrator, in selectively presenting the face side of the razor on either side of the vertical plane, and thus adapt the instrument for either right or left hand shaving, without displacing the vibrator from its preferably depending vertical position. Accordingly, another feature of the invention consists in securing the shank and vibrator together through means of concentric cylindrical members, carried one by the shank and the other by the vibrator, rotatable one within the other, and of which the inner cylindrical member is circumferentially slotted to admit the actuating end of the vibrator to the yoke of the connecting rod, and permit said inner cylindrical member to rotate in the aforesaid right and left hand adjustment of the razor; to which end, the yoke is likewise laterally open to the admission of the operating end of the vibrator through an angle of at least 180°. Preferably, the inner cylindrical member is held within the outer member by means of a plug united to the end of the inner cylindrical member in a manner to impart turning movement thereto, and said plug is fashioned in a manner to constitute it a convenient means for imparting the rotation incident to the right and left hand adjustment referred to.

Another object is to provide an improved driving connection for a vibratory razor blade of the type in which the blade, instead

of being mounted on a carriage which is guided for reciprocation, slides directly upon a fixed base upon which it is guided by pins extending through elongated holes in the 5 blade while receiving its drive from a stud intersecting its center, which driving connection will be substantially free from tendency to displace the blade from its axis of reciprocation, and therefore impose less wear 10 upon the guiding pins and less load upon the motor. Accordingly, another feature consists in providing at the center of the blade, and intermediate of its elongated guiding openings which occur near its ends, a hole 15 for the driving stud, which is of relatively large diameter as compared with the transverse diameter of the guiding openings and the width of the blade, the diameter of this driving hole being preferably somewhat more 20 than one-third of the width of the blade, with the result that a superior driving effect is insured, there is substantial reduction in the tendency to cause side impingement of the blade upon the aligning pins, and the arrangement admits of the use of a more stable 25 driving stud.

Further objects relate to details of construction which are particularly appropriate to the economical realization of the several 30 objects already stated, and will be fully understood from the ensuing detail description.

In the accompanying drawing Fig. 1 is a side elevation of a straight handled razor with the confining cap removed and a portion 35 of the handle in section, in an intermediate longitudinal plane of Figure 2;

Fig. 2 is a section on line 2^x—2^x of Fig. 1;

Fig. 3 is a transverse section on the line 3^x—3^x of Fig. 1;

Fig. 4 is a section on the line 4^x—4^x of Fig. 1;

Fig. 5 is a section on the line 5^x—5^x of Fig. 1;

Fig. 6 is a section on the line 6^x—6^x of Fig. 1; and

Fig. 7 is a section on the line 7^x—7^x of Fig. 1.

Figure 8 is a detail view of the spring clip that secures the cap to the blade mounting.

1 represents the base of the blade mounting, which is constructed with guard fingers 2, and which will be hereinafter referred to as the comb. 3 represents the blade resting upon the comb 1 and confined against displacement in the plane of the blade by means of the pins 4, fixed in the comb; and 5 represents the cover which confines the blade upon the comb and which is removably secured in place by means of a clip 6 having key hole slots 6^a (Fig. 8), which engage the necks 7 of the pins 4 and hold the cap at a fixed distance from the comb, thereby confining the blade without resisting its freedom of vibration. Preferably the cap 5 rests 65 firmly upon the heads of the pins 4, which

thus become the means for spacing the cap from the comb, and the clips 6 have sufficient resiliency to draw the cap snugly against the pins. 8 represents the handle which is in the form of a shank extending from the comb 1 substantially in the plane of the blade and thus adapting the razor to be manipulated after the manner of a so-called straight razor. The handle 8 is constructed of the shank 9 which extends from the comb and which is made trough-shaped for the dual purpose of lending rigidity to the structure and providing a portion of the housing for the connecting rod 10 that is to transmit vibration to the blade; also a cover member 11 which interlocks with the shank 9, by a sliding movement, and through the medium of tongue and groove joints 12. Shank 9 terminates at its outer end in a cylindrical ferrule 13 embraced by a sleeve 14, which equips the handle for receiving a vibrator, for instance, the vibrator 15, constructed substantially in accordance with my application hereinbefore identified; and the ferrule 13 is secured against axial displacement in the cylindrical sleeve 14 through means of a shouldered plug 16 entering the outer end of the sleeve 14 and at the same time abutting against the same, and a screw 17; the end of the ferrule 13 being constructed with a pair of segmental 95 walls 18, best shown by dotted lines in Fig. 6, which are lapped by the head of the screw, and the plug 16 being provided with a non-circular neck 16^a that enters the opening left between said walls 18 to adapt the plug, through its perforated end 16^b, to rotate the ferrule 13 and through it the shank 8 and head 1 of the razor.

Sleeve 14 provides for convenient assembly of the vibrator 15 through means of a 105 threaded bushing 19 fixed in the boss 20 of the sleeve and with which the vibrator 15 engages through the medium of its threaded end 21.

The connecting rod 10 confined in the tubular handle, as explained, is constructed on its outer end with a yoke 22 presented in position to receive the vibratory element 23 of the vibrator 15; said yoke 22, as better shown in Fig. 5, being designed to substantially fit and be guided in the ferrule 13, and being laterally open for at least 180° around its longitudinal axis to permit turning relatively to the vibratory element 23 in revolving the razor, and the said ferrule having an 110 arcuate slot 24 to admit the said vibratory element 23 within it, and extending circumferentially a distance which permits at least one hundred and eighty degrees of angular adjustment of the vibrator relatively to the plane of the razor blade. The inner end of connecting rod 10 is designed with a slide 25 fitted in a guide bed 26 which constitutes the bottom of the guard 1; and this slide 25 has a stud 25^a fixedly mounted in it in position to 130

extend through the blade 3 and thus serve as means for connecting the blade with the slide and causing the blade to partake of the slide's vibration.

- 5 In assembling the several parts as above described, the sleeve 14 being longitudinally fixed by means of plug 16 and screw 17 relatively to the ferrule 13 on the shank 9, and the vibrator 15 being removed, the connecting rod 10 with its slide 25 is first placed in position with its slot 25^b engaged over a pin 4, which brings the slide in its bearings in the bed 26, and presents its yoke 22 in position to receive the vibratory element 23. 10 Cover member 11 is then slid longitudinally along the shank 9, until its end 11^a (Fig. 2) brings up against the ferrule 13. The blade 3 is then placed in position with the posts 4 and the stud 25^a projecting through it, and cap 5 is put on and slid longitudinally toward the cover member 11 until it abuts against it. Vibrator 15 may be screwed into position at any time after the yoke of the connecting rod 10 has reached position to 15 receive vibrator member 23.

When thus assembled, the razor is supported by the vibratory housing 15 and turned, if necessary, to reverse the presentation of the facial side of the comb 1 to suit 20 the convenience of the user, and it is then manipulated in the act of shaving through the medium of the handle 8, such reversal to position being repeated as often as is necessary.

25 The device constructed and assembled, as herein described, is peculiarly adapted for production largely by shaping sheet metal of sufficiently thin gage to insure lightness of the parts and thus the construction and assembly are made very cheap and efficient in use.

I claim:

- 30 1. In a razor, a blade, a mounting supporting said blade with freedom of vibration thereon, a handle extending from said mounting, a connecting rod sliding in said handle, a vibrator extending transversely to said connecting rod and means for mounting the vibrator upon the handle, in driving relation 35 to the connecting rod, comprising a sleeve surrounding the handle, and having a transverse socket receiving the vibrator and admitting a portion thereof into the interior of the handle; said sleeve being rotatable upon the handle to permit the vibrator to assume different relative positions to the handle.

35 2. In a razor, a blade, a mounting for said blade, a handle extending from said mounting, a vibrator extending transversely from the handle, and means for uniting the vibrator with the handle consisting of a tubular ferrule carried by the handle, a sleeve surrounding said ferrule and receiving the vibrator and a plug and screw connection between the ferrule and the sleeve.

3. In a razor, a blade, a mounting supporting said blade with freedom of vibration thereon, a connecting rod for imparting vibration to said blade, and a handle surrounding said connecting rod; said handle comprising a shank and a cover member sliding into assembly with said shank and confining the connecting rod therein. 70

4. In a razor, a blade, a mounting for said blade, a shank extending from said mounting, and terminating in a ferrule, a connecting rod extending from the blade longitudinally of the handle, and a cover member enclosing the connecting rod in the shank, entering into sliding assembly with the shank 75 and abutting against said ferrule. 80

5. In a razor, a blade, a mounting for said blade, a shank extending from said mounting, a connecting rod extending from the blade longitudinally of the shank, a cover 85 member sliding into assembly with the shank and abutting against the same to limit such sliding movement, and a cap for confining the blade upon the mounting sliding into assembly with the mounting and abutting 90 against the cover member.

6. In a vibratory razor, a shank, and a transversely presented vibrator to which said shank is connected; said vibrator being adapted to swing about the longitudinal axis 95 of the shank to present the razor in different shaving positions.

7. In a vibratory razor, a shank, a transversely presented vibrator to which said shank is rotatably connected, and a member 100 projecting longitudinally from the shank beyond the vibrator and having connection through which it imparts rotation to the shank in changing the presentation of the razor relatively to the vibrator. 105

8. In a vibratory razor, a vibrator carrying a sleeve, a shank extending transversely to the axis of the vibrator, connecting the razor to the vibrator, and mounted for rotation in said sleeve, and a plug also mounted 110 for rotation in said sleeve, having connection through which it imparts rotation to the shank relatively to the vibrator in changing presentation of the razor.

9. In a vibratory razor, a mounting for 115 a vibratory blade, a shank extending from said blade mounting, a vibrator extending transversely from said shank at a point remote from said mounting, a sleeve carried by said vibrator in which the shank is rotatably supported, a connector slidably mounted in said shank and carrying a U-shaped yoke in alignment with the vibrator, said vibrator having a transmitting end received in said yoke, and said yoke and connecting rod being rotatable in the sleeve relatively to the vibrator and said transmitting end. 120

10. In a vibratory razor, a mounting for 125 a vibratory blade, a shank extending from 130

said mounting, a vibrator extending transversely from said shank at a point remote from said mounting, a sleeve carried by said vibrator and in which the shank is mounted 5 to rotate, a plug in the outer end of said sleeve opposite the end of said shank, and a screw passing through the end of the shank and into said plug.

11. A razor blade adapted to be mounted 10 in vibratory relation to a base; said blade having a single central hole in which it receives a vibratory driving element, and guiding openings adapted to receive aligning pins; said guiding openings being symmetrically disposed on opposite sides of the driving hole in the longitudinal axis of the blade, and being elongated in the direction of said axis to permit the blade to vibrate relatively to the aligning pins; and the 15 driving hole being of materially greater diameter than the transverse diameter of the guiding openings, and being of circular section.

12. A razor blade adapted for mounting 20 in vibratory relation to a support; said blade being constructed with guiding openings located in the longitudinal axis of the blade near its ends, and with a single driving hole of circular section disposed in the 25 geometrical center of the blade in alignment with the guiding openings; said driving hole having a diameter that is materially greater than the transverse dimension of the guiding openings and at least equal to 30 one third the width of the blade.

13. A razor having a blade mounted for 35 vibration in the plane of the blade, a handle extending from said razor in the plane of the blade, a vibrator mounted on said

handle at a point remote from the blade and 40 extending substantially perpendicularly to the handle and in the plane of the blade, and means transmitting vibration from the vibrator, through the handle, to the blade.

14. A razor having a blade mounted for 45 vibration in the plane of the blade, a handle extending from said razor in the plane of the blade, a vibrator mounted on said handle at a point remote from the blade and 50 extending substantially perpendicularly to the handle and in the plane of the blade, and means transmitting vibration from the vibrator, through the handle, to the blade; said vibrator being rotatable about the 55 axis of the handle and maintaining substantially 180° to bring it into right-hand and left-hand positions at will and maintaining driving connection with the vibration transmitting means in said rotation.

15. A razor having a blade mounted for 60 vibration in the plane of the blade, a handle extending from said razor in the plane of the blade, a vibrator mounted on said handle at a point remote from the blade and 65 extending substantially perpendicularly to the handle and in the plane of the blade, and means transmitting vibration from the vibrator, through the handle, to the blade; said vibrator being rotatable about the longitudinal axis of the handle substantially 70 180°, and the means transmitting vibration from the vibrator to the blade including a U-shaped yoke in which the vibrator engages, and with which it maintains its driving connection in said rotation. 75

Signed at New York, this 29th day of October, 1924.

SAUL SHALER.
